UNITED STATES PATENT OFFICE.

WILLIAM J. STEENROD, OF BENTON HARBOR, MICHIGAN, ASSIGNOR TO BAKER-VAWTER COMPANY, OF BENTON HARBOR, MICHIGAN, A CORPORATION OF MICHIGAN.

BINDER.

Application filed August 20, 1923. Serial No. 658,296.

My invention relates to a locking mechanism suitable for use in a form of loose leaf binders in common use commercially and including a pair of covers hinged to clamping bars or plates, one of the bars being equipped with binder posts (usually sectional) and the other being orificed to receive the posts and provided with locking mechanism adapted to cooperate therewith, so that a body of inserted leaves may be securely held between the bars. The object of my invention is to provide a novel locking mechanism of extremely simple construction, which can be readily and economically manufactured, and which shall have but few parts and be little liable to derangement, but shall be strong and efficient in serving the purposes for which it is designed. With this object in view, I have designed and invented the locking mechanism for binders hereinafter more fully described, and my invention resides in the formation, arrangement and construction of the cooperating parts and members of such mechanism, the essential elements thereof being more particularly pointed out in the appended claim.

In the accompanying drawings forming a part of this specification, Figure 1 is a longitudinal section of the clamping bars on a plane passing axially through the posts; Fig. 2 is a perspective broken away at the center, of the threaded end of the clamping bar and the clamping screw detached from the other parts; and Fig. 3 is a vertical section on a plane at right angles to the plane of Fig. 1. The same reference characters refer to the same parts in all the figures of the drawing.

The covers A of the binder may be connected to the clamping bars B by hinges in the usual manner, and one of the bars, the lower one shown in Figs. 1 and 3, is equipped with a pair of binder posts 1, as usual. The clamping bars may both conveniently be constructed of the telescoping sheet metal members 2 and 3, the hinge leaf 4 being secured, by spot welding or otherwise, to the outer face of the inner number 3.

Within the bar is slidably arranged the locking bar 5 which is formed of a longitudinally folded strip of sheet metal, U-shaped in cross-section from one end nearly to the other end. The bar is provided with

transverse orifices arranged to receive the binder posts, the one nearest the open end, marked 6, being of such size as to provide a loose fit and the other 7, preferably being slightly elongated. The sides of the bar are pinched together towards the outer end of the bar, beyond the post orifices 7 and on each side of semi-cylindrical bends 8, the two bends together forming a seat which is internally screw-threaded for the reception of the externally threaded inner end of the locking screw 9. The contacting faces of the pinched-in portion of the bar are firmly united on opposite sides of the bends 8 in suitable manner, preferably by spot welding.

The locking screw, as illustrated, is formed with a reduced bearing section 9^a providing a shoulder 10, and has a squared outer end 11. The end of the casing is closed by an end block 12, secured in place in the bar by set screws 13, and the block is bored to permit application of an operating key to the squared end of the locking screw and provides a smooth bearing for the reduced section 9^a thereof. The inner face of the block provides an abutment against which the shoulder 10 of the locking screw may react when the key is operated to release the locking mechanism.

As will be obvious from the description given, when the key is operated to draw the locking screw and locking bar together, the end of the screw will abut against the adjacent binder post 1 and draw the outer side of the orifice 6 at the opposite end of the bar against the other post, and thus stress the posts towards each other against the inner faces of the orifices in the upper and lower members of the clamping bars. While this mode of operation is not broadly new, the folded-over construction of the clamping bar provides a double bearing of relatively thin metal against the post at the open end of the bar which has been found particularly satisfactory and efficient, and the pinched-in construction and formation of the other end of the bar forms an extremely simple, strong and economically-constructed screw seat for the locking screw. The folded hollow sheet metal construction of the locking bar enables it to be made very light, and as the sides of such bar lie adjacent the walls of the clamping bar, with only sufficient clear-

ance to insure free relative movement of the parts, the locking bar operates accurately and smoothly.

I claim:

5. Clamping mechanism for a post binder including a clamping bar equipped with a pair of posts and a hollow clamping bar orificed to receive such posts; said mechanism comprising a longitudinally folded sheet metal locking bar slidably fitting within said hollow clamping bar, said locking bar having parallel sides adjacent the inner faces of said clamping bar orificed in alignment to re-

ceive said posts and arranged to clampingly engage a post at one end, and the sides of 15 the bar near the other end being formed with opposite semi-cylindrical bends arranged to together provide a central screw threaded seat communicating with the adjacent post orifice and being also formed with contiguous plane portions secured together on diametrically opposite sides of such seat, and comprising also a key-operated locking screw in said seat arranged to cooperate with the other locking post in said orifice.

WILLIAM J. STEENROD.
